UNITED STATES PATENT OFFICE.

NIC KRUMP, OF CHICAGO, ILLINOIS.

SWITCH FOR OVERHEAD TWO-RAIL TRACKS.

Application filed July 14, 1922. Serial No. 574,880.

To all whom it may concern:

Be it known that I, NIC KRUMP, a citizen of the United States, and a resident of Chicago, in the county of Cook and State of Illinois, have invented certain new and useful Improvements in Switches for Overhead Two-Rail Tracks, of which the following, when taken in connection with the drawings accompanying and forming a part hereof, is a full and complete specification.

This invention relates to switches to be installed in two rail over-head tracks, that is, two rail suspended tracks.

Among the objects of the invention are to obtain a two rail suspended switch which is easily erected and adjusted into the horizontal planes in which the rails leading to and from it are placed; to obtain what is known as a safety switch, that is, a switch which, when a trolley is approaching it on the rails leading to the free or movable ends thereof, said trolley cannot become derailed when the switch is not properly set to receive it; to obtain a switch of the kind named which comprises few parts, which is durable and not readily broken; and to obtain a switch which is easily set to be in line with any of the sets of rails at the free end thereof.

In the drawings referred to Fig. 1 is a top plan view of a switch embodying the invention.

Fig. 2 is a side elevation of said switch.

Fig. 3 is a horizontal section on line 3—3 of Fig. 2, viewed as indicated by arrows.

Fig. 4 is a vertical section on line 4—4 of Fig. 1, viewed as indicated by arrows.

Fig. 5 is a view on an enlarged scale, showing the pivoted end of the switch. And

Fig. 6 is a side elevation of the parts illustrated in Fig. 5.

Fig. 7 is a front elevation of the movable end of the switch.

45 A reference character applied to designate a given part indicates said part throughout the several figures of the drawings wherever the same appears.

50 A represents the suspended base which supports the rails leading to the switch and

also one end of the switch, and through which the depending bolts hereinafter described extend downward to and through the chairs in which said approaching rails are seated and secured, said chairs forming 55 sub bases. B represents a suspended sub base which supports the pivoted end of the switch, and the chair of the rails of the track at that end of the switch. a, a, and b, b, respectively represent apertures in bases 60 A and B, through which bolts are extended to secure said bases to beams or other structure from which the switch and rails are suspended. C represents an aperture in base A through which bolt C' extends downward 65 to the chairs D, D, and C'' represents a like downward extending bolt, which extends through a like aperture provided therefor in base B, and downward to and through chair D'. C''' an adjusting nut on the upper 70 end of bolt C''. E represents a metal member which is secured to bases A and B, by bolts e, e, to hold said bases in spaced relation. F represents a curved track on base 75 A, which is provided with depressions f, f, which are in spaced relation. G represents a carriage which is provided with rollers g, g, arranged to travel on track F, said rollers being in spaced relation corresponding with that of the depressions f, f. The 80 rollers g, g, and depressions f, f, are so arranged that when the rails on the switch are in line with the rails approaching the switch, on whichever one of the tracks the switch is 85 "set", said rollers will be in corresponding depressions, thus advising the party operating the switch that it is properly "set". X, X', X'', represent tracks approaching the switch, and Y represents the track approaching the switch at its opposite end. H, H, 90 represent downward extending bolts which are screw threaded at both ends, the upper ends thereof being adjustably secured in screw threaded apertures provided therefor in carriage G and the lower ends extending 95 through apertures therefor in chair I, (Fig. 2), said chair being adjustably mounted on said bolts by nuts h, h. The chair D is adjustably secured at the lower end of bolt C' by lock nuts h', and in addition thereto 100

said bolt C' is adjustable in base A, by nut h''. h''' represents like nuts on bolts H, H, respectively, which maintain said bolts in adjusted position, in carriage G. 5 J, J, represent bars or strips which are respectively secured to base A, by bolts J', J', and j, j', represent pulleys which are mounted on the ends of bars or strips J, J, respectively. K, K' represent cords or cables 10 which are attached to the carriage G and extend through pulleys j, j', respectively, and by means of which the carriage is moved to travel in the direction desired on track F, to properly set the switch. L represents 15 a curved member which is secured to carriage G, as by bolt 1, and at its ends, by rods M, M, to member N. Member N is rotatably mounted on bolt C'' (Fig. 2) said rods M, M, extending through apertures provided therefor in wings n, n, of said member N. Member N rests on washer n', and said washer is supported by nut n''. Member L is curved so as to obtain the recess L', (Fig. 7), through which the wheels of a 20 trolley travelling on the one of the tracks X, X', X'', to which the switch is set, may pass; and the remainder of said bar L, on both sides of recess L', forms a bar against which the wheels of a trolley on a track to 25 which said switch is not set abut, to prevent said trolley running off its track until the switch is properly set therefor. Z, Fig. 2, indicates a trolley wheel passing through said recess L', either in entering or leaving the 30 switch. O, O, represent the rails of the switch, and are formed by bending a rail, as at o', Fig. 3, so that the curved part will fit to the ends of rails Y, Y, (which are correspondingly bevelled) and the remainder 35 thereof will be parallel at the same distance apart as are the rails X, X', X'' and Y, of the tracks approaching and leaving the switch. P represents a bolt in base D' on 40 which the rails O, O, are pivoted. p represents a plate which rests on the lower flanges of rails O, O, and through which the bolt P also extends. P' represents a bolt which extends through plate p and into base D', by 45 means of which said plate is forced down on to the flanges of rails O, O, to hold said rails firmly to said base.

To operate the switch one or the other of 50 ropes or cables K, K' is pulled, and the carriage G thereby moved along track F until the switch becomes set for a given one of the tracks X, X', X''. The rollers g, g, of the carriage drop into corresponding recesses f, f, as the ends of rails O, O, come in line with the ends of the rails X, X', X'', respectively, so giving notice to the person operating the switch, and when said rolls drop into the depressions relating to the track to which it is sought to set the switch the rope or cable which is being pulled is released. 55 A trolley may then enter or leave the switch

from or on to the rails to which the switch is set. When so entering or leaving the switch the trolley wheel Z may and does pass through the recess L' in bar L, and in case, the switch being set for a certain track, a 70 trolley approaches the switch on another of the tracks, the wheel of said approaching trolley will strike or abut against the bar L to one side of the recess L', and will be blocked thereby. 75

I claim:

1. In a switch for overhead two rail tracks, bases, adapted to be suspended, a metal strip attached to said bases and arranged to hold them in spaced relation, rails on said switch 80 corresponding in length with the spaced relation of said bases, a curved track on one of said suspended bases, provided with depressions in spaced relation, a carriage, rollers on said carriage arranged to travel 85 on said track, said rollers in spaced relation corresponding with said depressions in said track, means to move said carriage on said tracks, and said carriage provided with a curved member to obtain a recess adapted 90 to permit a trolley wheel to pass therethrough on to or from said switch rails.

2. In a switch for overhead two rail tracks, bases, additional bases and means to adjustably suspend said additional bases from

said first named bases, a curved track on one of said first named suspended bases, said track provided with depressions in spaced relation, a carriage, rollers to said carriage arranged to travel on said track, said rollers in spaced relation corresponding to said depressions in said track, switch rails, means to adjustably suspend one end of said switch rails to said carriage and means to pivotally mount the other end of said switch rails on one of said second named suspended bases, tracks approaching said switch rails and supported by said second named and suspended bases, a curved member on the movable end of said switch, said curved member provided with a recess arranged to permit a trolley wheel entering or leaving said switch rails to pass therethrough. 105

3. In a switch for overhead two rail tracks, bases, sub bases, screw threaded bolts extending through said bases and through said sub bases, a curved track on one of said bases, in combination with a carriage arranged to travel on said track, means to

indicate when said carriage is in a determined position, screw threaded bolts extending from said carriage downward and through an additional sub base, an additional sub base, nuts on all of said bolts, a two rail track pivoted on one of said first named sub bases at one end of said track and mounted on said additional sub base at the other end thereof. 115

4. In a switch for overhead two rail tracks, bases, a curved track on one of said

bases, a carriage movable on said track, in combination with sub bases, one of said sub bases depending from said carriage and the remainder thereof depending from said 5 first named bases, the means for depending said sub bases comprising bolts threaded at both ends thereof, in combination with nuts on said bolts arranged to maintain said bolts in a determined position.

NIC KRUMP.
